UNITED STATES PATENT OFFICE.

FREMAN E. WOOD, OF ALPINE, MICHIGAN.

FENCE.

SPECIFICATION forming part of Letters Patent No. 381,047, dated April 10, 1883.

Application filed July 20, 1887. Serial No. 244,836. (No model.)

To all whom it may concern:

Be it known that I, FREMAN E. WOOD, of Alpine, in the county of Kent and State of Michigan, United States of America, have invented certain new and useful Improvements in Farm-Fences; and I do hereby declare that the following is a full, clear, and exact description of the same.

My invention relates to that class of fences which are adapted to be set upon the ground and moved about readily as circumstances may require, the object of the invention being to simplify and cheapen the construction and provide against the upsetting of the fence by the wind.

Referring to the accompanying drawings, Figure 1 is a perspective view of a portion of my improved fence. Fig. 2 is a vertical transverse sectional view on the line 1 1; Fig. 3, a horizontal sectional view on the line 2 2, and Fig. 4 a top plan view.

I am aware that prior to my invention farm-fences have been provided with crossed braces, rails, binders, and posts, the parts being connected by means of wires; and of course I make no claim, broadly, to such a fence.

I believe that my fence possesses material advantages over those which have heretofore preceded it, in that it is easily set up, is prevented from being upset or overturned by the wind, and is exceedingly cheap and simple in construction.

Referring again to the drawings, A, A', and A² represent the rails of the fence, the number of rails of course being varied according to the requirements of each case.

B B' represent the braces, which cross each other at a point above the upper rail, A², and which are adapted to receive in their upper forked ends a rider, C, as clearly shown in Figs. 1, 2, and 4.

D indicates a post which is adapted to rest upon the ground, as shown in Figs. 1 and 2, and which has its upper end beveled or cut at an angle, so as to support one of the posts B or B'.

Referring to Figs. 1, 2, and 4, I will describe the manner in which the rider is secured in the crotch of the braces B B'. The adjacent ends of the riders of two panels or sections of

the fence are laid side by side in the crotch formed by the braces, and a wire, E, is then passed about the outer face of each brace and over and down in between the ends of the riders, as shown. This construction tends not only to hold the riders down into the crotch formed by the braces, but also binds each rider to one of the braces, as will be clearly seen upon reference to Fig. 2. At a point immediately below the upper rail, A², and bearing against the under side thereof, is a wire, F, which is made in the form of a loop and passes about the braces B B', as clearly shown in Figs. 1 and 2. G indicates a wire, which is secured at its upper end to the post D, and which passes over the upper face of the rails A², thence downward along one face of said rails to near the bottom of the post, to which it is again secured, as clearly shown in Figs. 1 and 2. From this construction it will be seen that the upper rails, A², are encircled upon three sides by the wires F and G, and are firmly secured to and held in contact with the post D. Immediately below the second set of rails A' a loop, H, is passed about the post and about the downward extension of the wire G, so as not only to draw the wire G firmly against said rails, but so as to form a rest or support for the rails. From this it will be noticed that the braces are secured firmly together and also to the post, and that the binders and rails are also secured rigidly to the braces and to the post, thereby making a strong yet somewhat flexible or yielding fence that will adapt itself to any unevenness in the surface.

In order to give rigidity to the structure vertically, I make use of a binder, I, which extends diagonally across the faces of the rails equally on opposite sides of the upright post D, as clearly shown in Fig. 1. These binders will advisably be placed upon opposite sides of the fence, as also shown in Fig. 1, and are secured to the rider C by means of wire J, to the lower rail, A, by means of a wire, K, and to one of the braces and the upright post by means of a third wire or loop, L, as shown in Figs. 1, 2, and 3. The intermediate loop, L, passes about the post, upon the lower and upper faces of the binder and about one of the braces, as clearly shown in Figs. 2 and 3, and

as the binder is also secured to the rider and to the lower rail the rails are maintained in the proper vertical position.

In order to prevent the fence from being moved around by the cattle or by the wind, I employ a series of stakes, M, which are driven into the ground near the lower end of the binders, as shown in Figs. 1, 2, and 3, the wire loop K at the lower end of the binder passing about the said stake and also about the lower rail. The stake is the only part of the fence that is driven into the ground, and hence it will be seen that the fence above described may be set up without any previous preparation of the ground, which is a matter of considerable importance where the ground is frozen.

No claim is made by me to the crossed braces, the diagonal binder, the stake, nor to the bevelled post, as I am aware that these elements, separately considered, are old.

Having thus described my invention, what I claim is—

In a fence, the combination, with the crossed braces B B', adapted to merely rest upon the ground, of the upright post D, also adapted to rest upon the ground and having its upper end beveled to support one of the braces, riders C, resting in the upper crossed ends of the braces and secured to each other and to the braces by means of a wire, E, rails A A' A'', secured to the upright post D by means of wire G and loops H, diagonal binder I, secured at its upper end to the rider and crossing the rails between the braces, a stake, M, driven into the ground, and a wire, K, passing about the stake, the lower rail, and the binder, all substantially as shown.

In testimony whereof I affix my signature in presence of two witnesses.

FREMAN E. WOOD.
